(57) **CLAIM**

We claim the ornamental design for a lanyard attachment assembly, as shown and described.

DESCRIPTION

FIG. 1 is a front, perspective view of a lanyard attachment assembly showing our new design.

FIG. 2 is a right-side plan view thereof.

FIG. 3 is a rear perspective view thereof.

FIG. 4 is a left-side plan view thereof.

FIG. 5 is a top plan view thereof.

FIG. 6 is a bottom plan view thereof.

FIG. 7 is front plan view thereof.

FIG. 8 is a rear plan view thereof; and,

FIG. 9 is a front, perspective view of a lanyard attachment assembly installed on a tool (not claimed).

The broken line showing of a tool in FIG. 9 is included for the purpose of illustrating an example use of the tool with the claimed lanyard attachment assembly and forms no part of the claimed design.
